UNITED STATES PATENT OFFICE.

WILLIAM ATTAWAY, OF SPARTANBURG, SOUTH CAROLINA, ASSIGNOR TO DIXIE CAKE COMPANY, INC., OF SPARTANBURG, SOUTH CAROLINA, A CORPORATION OF SOUTH CAROLINA.

DESIGN FOR A BOX TOP.

Application filed October 19, 1925. Serial No. 15,166. Term of patent 14 years.

To all whom it may concern:

Be it known that I, WILLIAM ATTAWAY, a citizen of the United States, residing at Spartanburg, in the State of South Carolina, have invented a new, original, and ornamental Design for Box Tops, of which the following is a specification, reference being had to the accompanying drawing, forming a part thereof.

The figure is a plan view of a box top, showing my new design.

I claim:

The ornamental design for a box top, as shown.

WM. ATTAWAY.
